UNITED STATES PATENT OFFICE.

WILLIAM B. PRAYTOR, OF MOUNT PLEASANT, TEXAS.

SHOWCASE OR SCREEN.

1,389,898.

Specification of Letters Patent. Patented Sept. 6, 1921.

Application filed September 1, 1920. Serial No. 407,290.

To all whom it may concern:

Be it known that I, WILLIAM B. PRAYTOR, a citizen of the United States, residing at Mount Pleasant, in the county of Titus and 5 State of Texas, have invented a new and useful Showcase or Screen, of which the following is a specification.

It is the object of this invention to provide a simple means whereby pictures and 10 the like may be displayed from a cabinet, the construction being such that the pictures or other articles will be housed from the dust, when not in use, it being possible to open out the cabinet to render all of the pictures visible.

It is within the province of the disclosure to improve generally and to enhance the utility of devices of that type to which the invention appertains.

20 With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawings:—

Figure 1 shows in front elevation, a device constructed in accordance with the invention, the same being opened; Fig. 2 is a bottom plan wherein the cabinet is shown 35 opened; and Fig. 3 is a cross section wherein in the cabinet is shown closed.

The device forming the subject matter of this application includes a cabinet comprising a fixed side 1, cut away at its lower 40 end, as shown at 4, to form legs 5. A back 2 is provided and extends from the side 1 to an end post 3 extended downwardly to form a leg 6. A bottom 7 extends between the fixed side 1 and the end post 3 and is 45 cut away as indicated at 8, adjacent to the end post 3. The numeral 9 marks a top extended between the fixed side 1 and the end post 3, the top 9 being cut away as indicated at 10, in alinement with the place 50 where the bottom 7 is cut away as shown at 8.

The numeral 11 denotes a movable side, located opposite to the fixed side 1 and connected by hinges 12 to the post 3 which 55 may be considered as a part of the back of

the cabinet. A door 14 is hinged at 15 to the outer edge of the movable side 11. The side 11 is extended to form a leg 16 having a caster 17. A horizontal upper plate 18 is secured at 19 to the movable side 11. The 60 upper plate 18 is provided with a stop strip 20, received in the opening 10 of the top 9 and limiting the inward swinging movement of the side 11 when the side is swung to closed position. A lower plate 21 is secured 65 to the side 11, as indicated at 50, and is cut away as shown at 22, to receive the end post 3, the lower plate being cut away at its rear edge, as indicated at 23. A leaf 24 is hinged at 25 to the post 3. Sockets 26 are formed 70 in the upper plate 18 and in the lower plate 21, the sockets 26 being adapted to receive spindles 27 on leaves 28, there being any desired number of the leaves 28.

In practical operation, the movable side 75 11 is swung on the hinges 12 until the movable side is approximately parallel to the back, as indicated in Figs. 2 and 1. All of the leaves 28, thus, are swung out of the cabinet, and may be examined readily. 80 Since the bottom of the cabinet is cut away as indicated at 8, and since the top of the cabinet is cut away as shown at 10, access may be had to the leaves, when the leaves are swung out of the cabinet. When the 85 cabinet is closed, the side 11 is swung on the hinges 12 into approximate parallelism with the fixed side 1, the door 14 being swung to a closed position, as indicated in Fig. 3 of the drawings. The upper plate 18 covers the opening 10 in the top 9, the rear or inner portion 60 of the lower plate 21 closing the opening 8 and lying above the bottom 7.

Having thus described the invention, what 95 is claimed is:—

1. In a device of the class described, a cabinet comprising a back, a fixed side, a top and a bottom; a movable side hinged to the back and provided with outstanding top and bottom plates; a leaf mounted to swing in the top and bottom plates, the top and the bottom of the cabinet being cut away to give access to the leaf, and the top and bottom plates constituting closures for the cut 100 away portions of the top and the bottom; and a door hinged to the movable side.

2. In a device of the class described, a cabinet comprising a fixed side, a top, a bottom, and a back including an end post; a 110

movable side hinged to the end post; a top plate and a bottom plate carried by the movable side; a leaf mounted to swing in the top plate and the bottom plate, the top 5 and the bottom of the cabinet being cut away to define openings giving access to the leaf, and the top plate and the bottom plate constituting closures for the openings, the bottom plate being cut away to receive the

end posts; and a door hinged to the movable side.

In testimony that I claim the foregoing as my own, I have hereto affixed my signature in the presence of two witnesses.

WILLIAM B. PRAYTOR.
